TRIMMING AND CUTTING MACHINE

Edward M. Brackett, Dietrich Daneke, and Leo C. Williams, Topeka, Kans., assignors, by mesne assignments, to Dexter Folder Company, New York, N. Y., a corporation of New York (1934)

Application January 8, 1934, Serial No. 705,761

21 Claims. (Cl. 164—51)

Our invention relates to trimming and cutting machines and more particularly to those of that character for severing stacks of paper, as well as booklets, magazines, catalogs and other classes of sheet material that have been printed or assembled in gangs.

In machines of this character the cut-off knife and its carrier are constructed of relatively thick material in order to withstand the power required to cut relatively heavy stacks of sheet material. Consequently, the cut-off portion of the stack is disrupted due to displacement of the knife as the cut progresses through the depth of the stack.

It is, therefore, the principal object of the present invention to effectively apply a hold-down pressure upon the cut-off portion of the stack and to progressively shift the holding pressure to allow orderly racking movement of the cut-off portion to accommodate displacement of the knife.

Other objects of the invention are to apply an initial yielding pressure on the portion of the stack to be cut off during positioning thereof, to automatically operate the hold-down mechanism concurrently with the action of the knife, to retain a yielding pressure on the cut-off portion of the stack immediately following cutting operation of the knife, and to provide conveyor means to cooperate with the pressure applying means for removing the cut-off portions from the machine in spaced uniform sequence.

In accomplishing these and other objects of the invention we have provided improved details of structure, the preferred form of which is illustrated in the accompanying drawings, wherein:

Fig. 1 is a perspective view of a cutting machine equipped with a hold-down mechanism embodying the features of our invention.

Fig. 2 is an enlarged detail elevational view of a portion of the machine illustrating the mounting of the hold-down mechanism and showing the off-take conveyor in cross section.

Fig. 3 is an enlarged vertical section through the cutting mechanism and associated hold-down mechanism.

Fig. 4 is a similar section from the opposite direction illustrating the hold-down mechanism in functional position at the time the knife is descending in making the cut.

Fig. 5 is a similar section showing the position of the hold-down mechanism after the cut has been completed, and at the time the knife is ascending.

Fig. 6 is an enlarged detail perspective view of the hold-down mechanism.

Fig. 7 is a longitudinal sectional view of the hold-down mechanism.

Fig. 8 is a detail perspective view of the holding member.

Fig. 9 is a cross section through the hold-down mechanism on the line 9—9, Fig. 7.

Fig. 10 is a detail section illustrating the latch for retaining the holding member in retracted position on its support.

Referring more in detail to the drawings:

1 designates a cutting and trimming machine which includes a frame 2 having a vertical knife support 3 comprising vertically spaced guides 4 and 5 slidably mounting therebetween a knife-carrying member 6. The knife-carrying member includes a relatively heavy bar having its ends mounted in the guides 4 and 5 and provided with a downwardly inclined lower edge 7 adjacent a knife-seating shoulder 8 extending along the forward face thereof.

The knife 9 is secured in the shoulder portion 8 as in conventional practice and has a bevelled edge 10 projecting below the bevelled lower edge 25 of the knife carrier to form a cutting edge 11.

The frame 2 of the machine also includes a horizontal table 12 on which stacks of sheet material to be cut are fed under the knife.

Cooperating with the knife 9 and movable vertically in the knife support 3 is a clamping bar member 13 which descends into clamping engagement with the stack prior to the descent of the knife for clamping the stack to the table in position so that the cut is made in the proper place.

The knife carrier 6 and clamp member 13 are actuated by a suitable mechanism including an eccentric 14 mounted on a driven shaft 16 of a suitable transmission indicated by the housing 17, 40 a connecting rod 18 operably connecting the eccentric with a rocker arm 19, and a connecting link 20 connecting the rocker arm with the knife carrier, as illustrated in Fig. 1, the specific construction of which forms no part of the present invention.

The rocker arm 19, however, is fixed to a rock shaft 21 that is rotatably mounted in a housing 22 carried on the side of the frame below the table and which carries a driving clutch for actuating the holder mechanism as hereinafter described.

Extending from the trimming machine on the side opposite the cutter is a conveyor including a belt 23 having its upper run positioned in horizontal alignment with the table 12 to carry

severed portions of the sheet material from the trimming machine, the space between the table 12 and the end of the conveyor being bridged by a fixed apron 24 so that the projecting portions of the stacks that are to be severed by the knife are supported until the cut has been completed and the cut-off portions are ready to be moved onto the conveyor by the advance of the stack to make a succeeding cut.

10 In operating the machine thus briefly described, stacks of sheet material are moved across the table 12 so that the portion to be severed lies on the apron 24 and the point at which the cut is to be made is in vertical alignment with the cutting edge 11 of the knife blade. The knife mechanism is then actuated in a suitable manner to effect descent of the knife so that the cutting edge 11 thereof cuts across the stack to sever the portion supported on the apron 24 from that retained under the clamping bar 13.

15 As above pointed out the knife as well as its carrier is constructed of substantially thick material to provide rigidity and to assure a straight clean cut through the stack. Consequently, the inclined bevelled edges 7 and 10 displace the cut-off portion of the sheet material as the knife descends so that the cut-off sheets are widely dispersed and disarranged, and it is our purpose to retain the cut-off portions of sheets in orderly 20 stacked condition, for their successive delivery from the machine by the conveyor 22.

25 In carrying out the present invention we provide means for applying initial pressure to that portion of the stack that is severed by the knife while the stack is being positioned and the knife is descending and a cooperating holding means which is moved into clamping position with the stack concurrently with the cutting action of the knife to retain the sheet material in flat condition during the cut.

30 As the knife progresses into the stack, we provide for automatically shifting the holding means to incline or rack the cut-off portions of the sheet material to provide space for accommodating the knife displacement between the portion of the stack retained by the holder 13 and that portion supported on the apron 24, as now to be described.

35 Slidably mounted in the supporting frame 2 adjacent the knife guides 4 and 5 are inwardly extending guide ribs 25 cooperating with the inner face 26 of the frame for forming vertical tracks 27 for vertically positioned rack bars 28 and 29. The rack bars 28 and 29 have teeth 30 meshing with pinion gears 31 that are fixed to the ends of a shaft 32 which is rotatably mounted in brackets 33 and 34 carried by the knife-supporting frame, as best illustrated in Figs. 1, 2 and 3.

40 The brackets 33 and 34 include flange portions 35 fixed to the inner face 26 of the frame by cap screws 36 and have depending ears 37 rotatably mounting the shaft and engaging the inner face of the gear pinions to retain them in alignment 45 with the rack bars.

46 Slewed on the shaft 32 and having one end fixed to the bracket 33 and its opposite end fixed to a collar 39 is a coil spring 38 so tensioned as to counterbalance the weight of the rack bars 70 and the mechanism supported thereby, as later described, and for retaining the holding means in selectively adjusted vertical position. The rack bars are thus mounted for synchronous movement through the shaft 32 and the gear pinions meshing with the rack teeth.

5 In order to move the rack bars, the rack bar 29 carries a laterally projecting ear 40 on the inner face thereof which is connected by a link 41 with a rocker arm 42 on a rock shaft 43 that is pivotally mounted in the frame 2 at a point above the knife carrier, the link 41 being connected with the ear and with the free end of the rocker arm by pivotal connections 44 and 45, as illustrated in Fig. 3. The shaft 43 projects from the front face of the knife supporting frame and carries an operating lever 46 whereby the shaft 43 may be rotated to rock the arm 42 to cause vertical reciprocation of the rack bar on its supporting track. Reciprocation of the rack bar 29 causes similar movement of the other rack bar 15 through the gear pinions and shaft 32, as just described.

20 Formed on the lower end of the rack bars are forwardly extending bracket arms 47 and 48 supporting ends of a tie rod 49 that is secured there-to by cap screws 50.

25 Rotatably mounted in the rack bars at a point above the tie rod 49 is a rock shaft 51 which, with the tie rod and rack bars, constitutes a carriage 52 for supporting the holder mechanism now to be described.

30 The holder mechanism is best illustrated in Figs. 6 to 9 inclusive, and is shown as including a supporting member having a horizontally positioned body portion 53 provided with an integral tubular boss 54 on its upper face that is slidably mounted on the guide rod 49 and having upwardly extending spaced arms 55 and 56 carrying bearings 57 and 58 for receiving the rock shaft 51. The rock shaft thus cooperates with the guide rod 35 to support the body portion 53 in horizontal position relatively to the upper surface of the apron 24, as clearly shown in Fig. 3.

35 The supporting member thus described, while being retained against pivotal motion, is movable 40 longitudinally of the guide rod so that it may be positioned in alignment with the stacks of sheet material that are fed through the cutter and is adapted to be retained in selective position thereon by a thumb screw 60 threaded into an 45 opening 61 in a tubular portion 62 and having its end engaging against the guide rod, as shown in Fig. 7.

46 In order to provide an initial pressure on the portion of the stack to be severed by the knife, 50 we provide a yielding pressure applying means comprising a flat strip 63 of flexible material having its forward end 64 curved upwardly and rearwardly on substantially the arc of a circle and terminating in an attaching flange 65 for attachment to the forward end of the body portion 53 of the supporting member by screws 66 extending through suitable openings in the end of the strip and into threaded openings in the body portion 53. The rear end of the strip inclines upwardly below the body portion of the supporting member to a point in substantially vertical alignment with the rock shaft 50 and is slightly upturned, as at 67, to permit ready insertion of the stack of sheets thereunder.

55 Fixed to the rear end of the strip is a vertically positioned guide pin 68 that is slidably mounted in the bore 69 which is formed in a boss 70 depending from a web 71 connecting the arms 55 and 56. The guide pin 68 thus mounts the 70 rear end of the presser strip to permit yielding movement thereof in an upward direction.

60 In order to supplement the tension of the strip member we provide a pair of spring leaves 72 and 73 having their upper ends 74 fixed to the under 75

face of the body portion 53 and their lower ends curved downwardly and rearwardly and bearing on the upper face of the rearwardly extending portion of the strip, as shown in Fig. 7. To support and limit downward movement of the end 67 of the strip, against pressure of the supplemental spring leaves 72 and 73, the upper end of the guide pin 68 is provided with an opening 75 through which a cotter pin 76 is extended to engage the upper end of the tubular boss 70.

The pressing mechanism just described provides the initial pressure on the stack of sheet material prior to and while the knife is moving into contact with the stack and retains the severed sheet material in stacked condition as the severed portion of the stack is being moved onto the conveyor belt following the retractive movement of the knife. During the actual cutting operation of the knife, however, it is necessary to exert a greater pressure upon the stack to prevent upheaval of the end of the stack while the cut is being made.

In the present invention this is accomplished by a holding member 77 which is best illustrated in Fig. 8 and includes parallel side bars 78 and 79 spaced apart by cross rods 80 and 81 a sufficient distance to accommodate the body portion 53 of the supporting member therebetween, as clearly illustrated in Fig. 6. The cross rod 81 connecting the forward ends of the side bars forms a pivotal sliding support therefor on the forward end of the body portion 53. The cross rod 81 is mounted in downwardly opening notches 82 formed in depending flanges 83 and 84 of the supporting member, the bottom of the notches being closed by spaced bars 85 to form closed slots 86 which retain the cross bar for reciprocatory pivotal movement therein.

The rear end of the side bars 78 and 79 project rearwardly beyond the end 67 of the presser strip and are cut on rearwardly inclined planes 87 and connected by an inclined web 88 as best illustrated in Fig. 8, the ends and web 88 forming a cam surface to be engaged by the beveled portion 7 of the knife carrier when it descends in a cutting operation so that as the knife descends, the holder member is moved forwardly of the supporting member with the tie rod 81 sliding in the slots 82.

The holder member is normally retained in retractive position, that is, in position for engagement with the knife carrier by a spring 89 having one end fixed to a pin 90 on the end of the tubular boss 54 at a point adjacent the guide rod 49 and its other end to a projecting end 91 of the cross rod 81.

Under certain conditions the holder member may be selectively latched and retained from engagement with the knife bar by a latch 92 pivotally mounted on a pin 93 projecting from the side face of the body portion 53 of the supporting member on the side thereof adjacent the side bar 78 and which has a hook or detent portion 94 adapted to engage over the tie rod 81 when the holder is in retracted position, as illustrated in Fig. 10. By thus latching the tie bar with the detent portion of the latch, the spring 89 is prevented from effecting retraction of the holder and the holder is retained from contact with the knife carrier.

In order to apply pressure on the holding member concurrently with movement of the knife into cutting engagement with the sheet material, the tie rod 80 thereof is operably con-

nected with the rock shaft 21, as now to be described.

Fixed on the outer end of the rock shaft 21 is a clutch disk 95, frictionally engaged by a complementary clutch disk 96 loosely mounted on the shaft and having a depending arm 97 that is connected by a link 98 with a rocker arm 99. The rocker arm 99 is fixed to the end of a rock shaft 100 that is rotatably mounted in a bearing 101 carried by the frame of the machine at 10 a point below the table 12, as best illustrated in Figs. 1 and 2.

Fixed to the opposite end of the shaft 100 is a crank arm 102 that is connected with a crank arm 103 on the rock shaft 51 mounted on the carriage 52, the arms 102 and 103 being connected by a link 104.

It is thus apparent that when the arm 19 rocks the shaft 21, the disk 95 will drive the disk 96 to move the arm 97 thereon in an arc from the axis of the shaft. Movement of the arm 97 operates the rock shaft 100 through the crank arm 99 and operation of the rock shaft rocks the shaft 51 through the arms 102, 103 and their connecting link 104 to move the arm 103 in an anti-clockwise direction, Fig. 4. Movement of the arm 103, however, is limited by a pin 105 on the rack bar 28 which is engaged by the depending lug 106 on the arm. When the lug on the arm engages the pin, it will stop rotation of the shaft but the shaft 21 is free to continue its movement under influence of the arm 19 due to the slip clutch disks 95 and 96.

Slidably mounted on the shaft 51 between the bearings 57 and 58 is an arm 107 projecting forwardly in the direction of the body portion 53 of the supporting member and which is keyed to the shaft 51 by a spline 108 extending longitudinally of the shaft, as shown in Fig. 7. The forward end of the arm 107 is forked to provide spaced bearing portions 109 and 110 for mounting trunnions 111 and 112 on a block 113 whereby the block is supported between the forks of the arms to adjustably mount a connecting link 114. The block 113 is provided with a vertical bore 115 for passing the upper threaded end 116 of the link 114 that is adjustably positioned therein by lock nuts 117 and 118 threaded on the link and engaging opposite faces of the block.

The lower end of the connecting link 114 is provided with a head 119 having a transverse opening 120 therethrough for loosely receiving the cross rod 80 on the holder member. When the shaft 51 is being moved in an anti-clockwise direction, Fig. 4, or in a clockwise direction, Fig. 7, the connecting link 114 moves the rear or cam end of the holder member downwardly in an arc from the axis of the cross rod 81 and into pressing engagement with that portion of the stack that has been delivered under the path of the knife. Pressure will be retained upon the holder member during the entire movement of the knife due to the frictional contact of the clutch disk 95 with the disk 96, the extent of movement of the holder member depending upon the height of the stack, the adjustment of the link 114, or by the selective position of the carriage.

Should the lug on the arm 103 engage the stop pin 105 before the desired pressure is applied, it is necessary to lower the carriage. This can be readily accomplished through the lever 46 so that when the holder member is engaged with the stack, there is sufficient movement of the shaft 51 to apply the required pressure in holding the sheet material in position while the cut is being 75

made. A more limited adjustment might be made through adjusting the link 114 in the block 113.

Upon return movement of the knife the shaft 51 will be rotated in reverse direction to raise the holder member from contact with the stack but the pressure strip will remain in contact therewith to support the sheets while they are being forwarded onto the conveyor belt 23 upon advancing the stack of sheet material for cutting off another portion.

In using a trimming machine equipped with a holding mechanism constructed and assembled as described, the stacks of sheet material are moved across the table 12 until the place where the cut is to be made aligns with the point of travel of the knife edge. The carriage will then be lowered until the presser strip is in desired pressing contact with the top of the stack by rotating the lever arm 45 in an anti-clockwise direction to cause the arm 42 to lower the rack bar through the connecting link 41. Movement of the rack bar 29 causes similar movement of the other rack bar due to their geared connection through the pinions 31 and shaft 32 to lower the carriage supporting the holding mechanism. If it is necessary to raise the holding mechanism, this can be accomplished by reverse movement of the lever 46.

The machine will then be operated to cause the knife to move downwardly toward the stack, but the initial movement of the knife first effects movement of the clamping bar 13 into clamping engagement with the top of the stack before the cutting edge of the knife engages the uppermost sheet.

Concurrently with the movement of the knife and just before the cutting edge thereof engages the stack, the holder member will have been moved into pressing contact with the stack through the driving connection of the clutch disks 95 and 96, arm 97, connecting link 98, arm 99, rock shaft 100, arm 102, connecting link 104, arm 103, shaft 51, arm 101, and the connecting link 114. The holding pressure will be retained on the stack during the entire downward movement of the knife due to slipping engagement of the clutch disks.

As soon as the inclined face of the knife carrier engages the inclined cam end of the holder, the holder will be moved forwardly, thereby to rack the stack of sheets progressively with the downward movement of the knife, as illustrated in Fig. 4.

By racking movement of the stack is meant movement thereof in a direction to provide space between that portion of the stack held between the clamp bar 13 and the severed sheets that are held in pressed condition by the holder member, which space accommodates displacement of the knife.

Upon upward movement of the knife the spring 89 will return the holder member as soon as the pressure is relieved through reverse rotation of the clutch disks.

At the upper limit of movement of the knife, the holder member has reached the upward limit of its travel but the presser strip 63 retains its pressing contact with the stack to hold the sheets in orderly arrangement while they are being moved onto the conveyor belt.

From the foregoing it is apparent that we have provided a holder mechanism which will effectively hold the sheets in stacked relation while a cut is being made and which controls racking or tilting movement of the stack in a forward direc-

tion to accommodate displacement of the knife and its carrier so that the stack of sheets when moved onto the delivery belt are in orderly stacked relation.

What we claim and desire to secure by Letters Patent is:

1. In combination with a cutter for severing a portion of a stack of sheet material, means for applying pressure to said portion, and means for effecting shifting movement of the sheet material cut off progressively with movement of the cutter through the stack.

2. In combination with a cutter for severing a portion of a stack of sheet material, a holder applying pressure to said portion of the stack, means supporting the holder for lateral shifting movement relatively to the cutter, and means for actuating the holder concurrently with operation of the cutter to rack the cut off portion of the stack for accommodating cutter displacement during the cutting operation.

3. In combination with a cutter for severing a portion of a stack of sheet material, a holder for applying pressure to a portion of the stack to be cut off, means for supporting the holder for lateral shifting movement relative to the cutter, means carried by the holder for applying an initial pressure to said portion of the stack, and means for moving the holder concurrently with operation of the cutter to rack the cut off sheets of the stack for accommodating cutter displacement during the cutting operation.

4. In a machine of the character described including a support, a cutter carried by the support, mechanism for actuating the cutter to sever a portion of a stack of sheet material, a holder, means supporting the holder for movement on the support, and holder operating means carried by the support and having a slip connection with said cutter operating means to move the holder into pressing contact with said portion of the stack and provide for continued operation of said mechanism.

5. In a machine of the character described including a support, a cutter carried by the support, means for actuating the cutter for severing a portion of a stack of sheet material, a holder, means supporting the holder for pivotal and sliding movement on the support, means carried by the support and actuated by said cutter operating means for pivoting the holder into pressing contact with said portion of the stack, and means mounted with the cutter for engaging the holder to effect sliding movement thereof for racking the cut off portion of the stack progressively with the severing operation by the cutter.

6. In a machine of the character described including a support, a cutter carried by the support, means on the support for actuating the cutter for severing a portion of a stack of sheet material, a holder for pressing upon a portion of the stack to be cut off, means supporting the holder for movement on the support, means carried by the holder for applying initial pressure to said portion of the stack, and means connected with said cutter operating means for moving the holder into pressing contact with said portion of the stack.

7. In a machine of the character described including a support, a cutter carried by the support, means on the support for actuating the cutter for severing a portion of a stack of sheet material, a holder for pressing upon a portion of the stack to be cut off, means supporting the holder for pivotal and sliding movement on the support,

- means carried by the holder supporting means for applying initial pressure to said portion of the stack, means connected with said cutter operating means for pivoting the holder into pressing contact with said portion of the stack, and means movably mounted with the cutter for engaging the holder to effect sliding movement thereof for racking the cut off portion of the stack progressively with the severing operation by the cutter.
- 5 8. In combination with a cutter for severing a portion of a stack of sheet material, a holder, means supporting the holder for swinging and lateral shifting movement thereof relative to the cutter, and means for swinging and laterally shifting the holder concurrently with operation of the cutter to press the holder against the cut-off portion of the stack, fan-out or rack the cut off portion of the stack and accommodate cutter displacement in the stack during the cutting operation.
- 10 9. In a machine of the character described including a support, a cutter carried by the support, means for actuating the cutter for severing a portion of a stack of sheet material, a holder for pressing upon a portion of the stack to be cut off, means adjustably mounting the holder on the support for position relatively to the stack of sheet material, and actuating means connecting said cutter actuating means with the holder for moving the holder into pressing engagement with said portion of the stack.
- 15 10. In a machine of the character described including a support, a cutter carried by the support, means for actuating the cutter for severing a portion of a stack of sheet material, a holder for pressing upon a portion of the stack to be cut off, means slidably mounting the holder on the support for position relatively to the stack of sheet material, actuating means connecting said cutter actuating means with the holder for moving the holder into pressing engagement with said portion of the stack, and yielding means on the holder mounting means for initially pressing the stack prior to engagement of the holder.
- 20 11. In a machine of the character described including a support, a cutter carried by the support for severing a portion of a stack of sheet material, means on the support for actuating the cutter, a carriage, means mounting the carriage for vertical movement on the support, a holder mounted on the carriage, means for moving the carriage to bring the holder into selective position relatively to the cutter, yielding means on the carriage for initially engaging the stack, and means on the carriage for moving the holder into pressing engagement with the stack during operation of the cutter.
- 25 12. In a machine of the character described including a support, a cutter carried by the support for severing a portion of a stack of sheet material, means on the support for actuating the cutter, a carriage movable vertically on the support, a supporting member slidably mounted on the carriage, a holder member pivotally and slidably mounted on the supporting member, means on the carriage for pivoting the holder member into pressing contact with the portion of the stack to be severed, and means carried with the cutter and engaging said holder member for sliding the holder member on the supporting member to effect racking movement of said portion of the stack upon actuation of the cutter.
- 30 13. In a machine of the character described including a support, a cutter carried by the sup-
- port for severing a portion of a stack of sheet material, means on the support for actuating the cutter, a carriage movable vertically on the support, a supporting member mounted on the carriage, a holder member mounted on the supporting member, and means on the carriage for moving the holder member into pressing contact with the portion of the stack to be severed.
- 35 14. In a machine of the character described including a support, a knife reciprocably mounted on the support, means on the support for actuating the knife, a pair of rack bars slidably mounted on the support, a shaft carried by the support, gears on the shaft meshing with the rack bars, means on the support for moving one of the rack bars to effect movement of the other, a guide member carried by the rack bars and extending longitudinally of the knife, a rock shaft rotatably mounted in the rack bars, a holder carrying member slidably mounted on the rock shaft and guide member, a rocker arm on the rock shaft, a pressing member supported on the holder carrying member for applying initial pressure to a stack of sheet material to be cut by the knife, a holding member pivotally and slidably mounted on the holder carrying member, a link connecting the rocker arm with the holding member, means connecting the rock shaft with said knife actuating mechanism to effect movement of the holding member into engagement with the stack upon actuation of the knife.
- 40 15. In a machine of the character described including a support, a knife reciprocably mounted on the support, means on the support for actuating the knife, a carriage slidably mounted on the support, a guide member on the carriage and extending longitudinally of the knife, a rock shaft rotatably mounted on the carriage, a holder carrying member slidably mounted on the rock shaft and guide member, a rocker arm on the rock shaft, a pressing member yieldingly supported on the holder carrying member for applying initial pressure to a stack of sheet material to be cut by the knife, a holding member pivotally and slidably mounted on the holder carrying member, a link connecting the rocker arm with the holding member, means connecting the rock shaft with said knife actuating mechanism to effect movement of the holding member into engagement with the stack upon actuation of the knife, and means carried by the knife engaging the holding member for sliding the holding member for effecting racking movement of the stack during actuation of the knife.
- 45 16. In a machine of the character described including a support, a knife reciprocably mounted on the support, means on the support for actuating the knife, a pair of rack bars slidably mounted on the support, a shaft carried by the support, gears on the shaft meshing with the rack bars, means on the support for moving one of the rack bars, a guide member carried by the rack bars and extending longitudinally of the knife, a rock shaft rotatably mounted in the rack bars, a holder carrying member slidably mounted on the rock shaft and guide member, a rocker arm on the rock shaft, a pressing member supported on the arm for applying initial pressure to a stack of sheet material to be severed by the knife, a holding member pivotally and slidably

- mounted on the holder carrying member, a link connecting the rocker arm with the holding member, means connecting the rock shaft with said knife actuating mechanism to effect movement of the holding member into engagement with the stack upon actuation of the knife, means carried by the knife engaging the holding member for sliding the holder member on said carrying member for effecting racking movement of the stack during actuation of the knife, and means for retracting the holding member upon reverse movement of the knife.
17. In a machine of the character described including a support, a knife reciprocably mounted on the support, means on the support for actuating the knife, a pair of rack bars slidably mounted on the support, a shaft carried by the support, gears on the shaft meshing with the rack bars, means on the support for rotating the shaft to effect movement of the rack bars, a guide member carried by the rack bars and extending longitudinally of the knife, a rock shaft rotatably mounted in the rack bars, a holder carrying member slidably mounted on the rock shaft and guide member, a rocker arm on the rock shaft, a pressing member yieldingly supported on the arm for applying initial pressure on a stack of sheet material to be severed by the knife, a holding member pivotally and slidably mounted on the holder carrying member, a link connecting the rocker arm with the holding member, means connecting the rock shaft with said knife actuating mechanism to effect movement of the holding member into engagement with the stack of sheet material to be severed upon actuation of the knife, means carried by the knife engaging the holding member for sliding the holding member on the carrying member for effecting racking movement of the stack during actuation of the knife, means for retracting the holding member upon reverse movement of the knife, and a latch pivoted on said carrying member engaging the holding member for retaining the holder member in retractive position.
18. In a machine of the character described including a support, a cutter carried by the support for severing a stack of sheet material, means on the support for actuating the cutter, a carriage movable vertically on the support, a holder support slidably mounted on the carriage, a holder member pivotally and slidably mounted on the holder support, means on the carriage for pivoting the holder member into pressing contact with the portion of the stack of sheet material to be severed, means carried with the cutter and engaging said holder member for sliding the holder member on the holder support to effect racking movement of said portion of the stack upon actuation of the cutter, and means for counterbalancing the carriage on the support to retain the carriage in selective position relative to the stack.
19. In a machine of the character described including a support, a cutter carried by the support for severing a stack of sheet material, means on the support for actuating the cutter, a carriage movable vertically on the support, a holder member mounted on the carriage, means for moving the holder member into pressing contact with the portion of the stack to be severed, and means for counterbalancing the carriage on the support to retain the carriage in selective position relative to the stack.
20. In a machine of the character described including a support, a knife reciprocably mounted on the support for severing a stack of sheet material, means on the support for actuating the knife, a carriage including a pair of rack bars slidably mounted on the support, a shaft carried by the support, gears on the shaft meshing with the rack bars, a spring coiled on the shaft for balancing the carriage on the support, a guide member carried by the rack bars and extending longitudinally of the knife, a rock shaft rotatably mounted in the rack bars, a holder carrying member mounted on the carrier for applying pressure to the stack during actuation of the knife, and means for raising and lowering the carriage against the balancing action of the spring.
21. In combination with a cutter for severing a portion of a stack of sheet material, and means for actuating the cutter, a holder for applying pressure to a portion of the stack to be cut off, means for supporting the holder for movement relative to the cutter, and means connecting the holder with the cutter operating means including a slip clutch for moving and retaining the holder in pressing contact with the stack.
